OSCILLATING MEANS FOR RADIANT
HEATERS

Laurence S. Harrison, Bronxville, and Allen A. Canton, New York, N. Y., assignors to Technical Research Products Corporation, New York, N. Y., a corporation of New York

Application December 30, 1938, Serial No. 248,464

7 Claims. (Cl. 219—34)

This invention relates to dirigible means for radiant electric heaters and the like and has for an object the provision of improvements in this art. In particular the invention aims to provide improved means and method for controlling the position of heat emitting means by and in accordance with the heat emitted.

Radiant electric heaters, as found on the market at present, do not distribute heat but project it in a fixed limited zone with the result that there is an undue concentration of heat directly in front of the reflector and an almost complete absence of heat at all other places. For serving one person in a fixed position or for merely tempering the atmosphere in a cold room, a fixed radiant heater has some value, but it is far from being adequate or satisfactory where more spread and less concentration of heat are desired. It is quite common to shift a radiant heater by hand at frequent intervals in order to serve more than one or two people, and these usually take turns being scorched or frozen before the heater can be shifted.

There are also other devices supplying heat either purposely or incidentally which require oscillation or orientation and which can usefully employ the present invention. Searchlights may be mentioned as an example.

Heretofore it has been proposed to serve radiant heaters by blowers or fans to avoid undue concentration of heat. It has also been proposed to employ motors for oscillating the heaters, the motors often being employed for operating fans. For such devices there may be a distinct field, but they are quite expensive and heavy and the motors often overheat or become oil-dry because of their proximity to the heating elements and the necessary metal mountings.

The present invention provides oscillating means for radiant heaters, searchlights and similar devices, which is very simple, light, durable and inexpensive; which can be adjusted as to speed of action or rendered inoperative at will; and which is entirely reliable in service.

According to the invention the oscillation is produced by the radiated heat of the heating element itself, and requires only a small portion of this heat for only part of the time. This avoids the use of motors and other devices which consume relatively large amounts of current continuously and which besides are expensive, heavy and bulky.

The invention will best be understood by reference to an illustrative embodiment which is shown in the accompanying drawings wherein:

Fig. 1 is a front elevation of a radiant electric heater embodying the present invention;

Fig. 2 is a side elevation;

Fig. 3 is a partial enlarged vertical section taken on the line 3—3 of Fig. 1;

Fig. 4 is a section taken on the line 4—4 of Fig. 3;

Fig. 5 is an enlarged elevation of the trip mechanism, the view being taken on the line 5—5 of Fig. 3;

Fig. 6 is a left side elevation of Fig. 5 or an enlargement of a portion of the mechanism shown in Fig. 3; and

Fig. 7 is an elevational view taken on the line 1—1 of Fig. 3, showing the shutter mounting.

Referring to the drawings, the device includes a base 10, a pedestal 11, a reflector 12, a resistance heating device 13, a guard 14, an escutcheon casing 15, a casing or cover 16 for the oscillating mechanism, and a lifting handle 17. The pedestal 11 may be hinged upon a pivot pin 18 in order that the reflector 12 may be tilted at various angles about a horizontal axis. As shown in Fig. 3, the heating device 13 may be threaded into a receptacle 19 connected to a source of electric current. In Fig. 2 an electric cord 20 is shown for connecting the device with an electric circuit.

Again referring to Fig. 3, the receptacle 19 is secured in the front wall 12a or reflector proper of the reflector 12, and the rear wall 12b is used as a supporting means for the front wall and for certain related mechanism for oscillating the heating device, as will be presently described.

The supporting wall 12b is secured, as by a bolt 23 and nut 24, to a mounting piece 25 which is rotatably mounted on a swivel post 26 fixedly secured in the upper end of the pedestal 11, as by a set screw 27. The mounting piece 25 is retained on the swivel post 26 by a castellated headed member or bull ring gear 28 which may be formed integrally on the post 26; or, as shown, it may have a projection which is threaded into the upper end of the post and held by a pin 29. The member 28 may be secured to the post 26 before the post is passed through the hole or bearing in the mounting piece 25 and placed in the bore of the pedestal. A ball bearing race 30 and a bearing washer 31 may be placed between the mounting piece 25 and the upper end of the pedestal to facilitate easy oscillatory movement.

Means are provided for oscillating the reflector and associated parts, this oscillating means preferably being operated by heat radiated from the heating device 13. As shown herein, the oscillating means is operated directly by power created

by radiant heat, but it may be operated by secondary power, if desired, and merely receive its power initiating impulses from the source of heat or light radiation of the heating device 13.

- 5 The oscillating means may take its reaction from the bull ring gear 28 which, as stated, is rigidly secured to the top of the pedestal 11. Conveniently, the relative movement is produced by a gear segment 35 fixed on an oscillating shaft 10 36 which is rotatably mounted in spaced bearings in upstanding portions 25a and 25b of the mounting piece 25.

15 The front end of the oscillating shaft 36 operates escapement mechanism for controlling the action of a radiation regulating shutter 37 mounted adjacent slits 38, 39 in the reflector walls 12a, 12b; while the central portion of the shaft carries a fixed arm 40 through which the shaft is actuated by a connecting member 41 of 20 a power device 42 responsive to the presence or absence of radiant energy passing through the slits 38, 39. The U-shaped shutter 37 may be formed of a flexible heat-resistant material such as mica, if desired.

25 The power device 42 may assume various forms, one type of which may be a thermostat of some kind. The power means shown herein comprises a thermostat proper 43 such as a container for liquid, a tube 44 for conveying the 30 liquid from the container, and an expansion power applying device in the form of a Sylphon bellows 45 receiving liquid from the tube. The thermostat container 43 and the Sylphon bellows 45 are mounted on brackets 46, 47 secured within 35 the escutcheon casing 15. The bellows 45 is provided with a connecting rod 48 guided in an opening in a fixed bracket 49 and this rod carries the connecting member 41, previously referred to, which actuates the shaft arm 40.

40 Referring to Figs. 3 and 7, the shutter 37 is shown to be formed as a U-shaped member pivoted at 52 and 53 to the front and rear walls 12a, 12b of the reflector beneath the slits 38 and 39. An arm 54 secured to the lower edge of the shutter 45 serves to operate the same from a vertically reciprocating shutter operating link 55. The link 55 is mounted in loose fitting slots in the spaced arms of a bracket 56 secured to the rear wall 12b of the reflector.

50 It will be observed that when the U-shaped shutter swings down from its vertical position it will at once cease to bind against the spaced reflector walls except at its lower ends, though it may have enough spring to maintain a tight fit 55 at its lower ends to avoid noise.

It will also be clear that when the shutter is in its lower position the slits 38 and 39 are open whereby to permit the passage of radiant heat from the heating device 13 to the thermostat 43.

60 This heat causes the fluid within the thermostat container to expand into the tube 44 and the Sylphon bellows 45, thus operating the shaft 36 in one direction. When the shutter closes the slits the thermostat no longer receives radiant heat from the heating device 13 and begins to cool. The cooling is assisted by an induced flow of cool air through the escutcheon casing by the provision of air inlet openings 57 in the lower part of the escutcheon casing and air outlet openings 58 in the upper part of the casing. The Sylphon bellows is resilient and tends to contract as the fluid cools to force the fluid back into the thermostat container and simultaneously oscillate the shaft 36 in the other direction.

70 The shaft 36 operates the escapement mecha-

nism which controls the movement of the shutter. This assures that the reflector will make a full stroke in one direction before it reverses direction and makes a full stroke in the other direction. This escapement mechanism is shown in Figs. 5 and 6.

Near its front end the oscillating shaft carries fast thereon an oscillating depending arm 60 to the lower end of which a leaf spring 61 is secured as by rivets 62. Conveniently the arm 60 is provided with a forwardly extending finger 63 to which the spring is riveted. On the extreme front end of the shaft 36 there is loosely mounted a shutter operating lever 64. This lever is provided with two spaced pairs of spaced fingers 65a, 65b which extend forward beyond the end of the shaft 36 and loosely receive the leaf spring 61. For smooth action the pairs of fingers are placed at equal distances from and on opposite sides of the axis of the shaft 36. The spring, being secured against axial or edgewise movement because it is fastened by two rivets, as shown in Fig. 6, prevents the lever 64 from coming off the end of the shaft 36.

The lever 64 is provided with an arm 64a to which the shutter operating link 55 is connected and an arm 64b which cooperates with an escapement verge 66 rotatably mounted on a fixed stud 67 secured to the front upstanding portion 25a of the mounting piece 25. The verge 66 is constantly urged toward a central position by a spring pin 68 which passes through a hole in the end of the stud 67 and through holes in lugs 69 formed on the verge on opposite sides of the stud axis. The pin also serves to retain the verge on the stud. The pin may be retained in the lugs in any suitable manner, as by having its upper end bent, as shown.

The central position of the verge **66** is slightly to the right, in anti-clockwise direction, of the position in which it appears in Fig. 5. In the Fig. 5 position the verge has just been pushed to the left to permit operation of the shutter actuating lever **64**.

The verge comprises two arms 70 and 71, carrying at their respective lower ends the laterally extending escapement ears 72, 73 which cooperate with a laterally extending retaining ear 74 formed on the latch arm 64b of the lever 64. The arm 64b is formed integrally with the shutter operating arm 64a of the lever 64.

Means are provided for tripping the verge 66 to time the shutter operation. The means shown comprises a cam arm 75 which is rigidly secured to the oscillating shaft 36, as by being formed integrally with the oscillating arm 60 which carries the spring 61. The end of the cam arm 75 has a rounded nose which is positioned in the plane of the arms 70 and 71 of the verge. The inner edges of the arms 70 and 71 are formed with cam surfaces 70a and 71a which are disposed in the path of the end of the cam arm 75. In Fig. 5 the arm 75 has just acted upon the cam 71a to push the verge to the left.

Shortly thereafter the oscillating shaft reverses direction and moves the oscillating spring supporting arm 60 and the cam arm 75 to the left, i. e., clockwise. This causes the cam arm 75 to release the arm 71 of the verge and permit it to move to the right, i. e., anti-clockwise, until the ear 73 thereof is directly above the top of the ear 74 of the latch arm 64b. The spring supporting arm 60 now continues to move in a clockwise direction; but the lever 64 cannot turn because its latch arm 64b is held by the verge ear 75.

73, as stated. What happens, therefore, is that the spring 61 is bent to put the arm 64 under tension. As the arm 60 moves further the cam arm 75 advances correspondingly until it engages the cam 70a of the upper verge arm 70 and moves the verge in an anti-clockwise direction from its central position. This moves the ear 73 beyond the inner edge of the ear 74 of the latch arm 64b and releases the latter. The spring tension causes it to move upward and carry the arm 64a downward to open the shutter.

When the latch arm reaches the upper position the lower side of its ear 74 engages the outer side of the ear 72 of the upper verge arm 70. This holds the latch arm in upper position while the spring arm 60 and the cam arm 75 move to lower position and the latter, by action on cam surface 71a of verge arm 71, releases the latch arm. This brings the parts back to the position in which they appear in Fig. 5, meanwhile closing the shutter. It is to be noted that the ear 74 of the latch arm is always engaged from its outer edge and disengaged from its inner edge. Stated another way, the ears 72 and 73 of the verge engage the latch ear 74 from their inner or adjacent edges and release it from their outer or distant edges.

It has already been seen how the opening and closing of the shutter energizes and de-energizes the thermostat; how this oscillates the shaft 36; and how the gear segment 35 of the shaft, acting against the fixed bull ring gear, causes the reflector and heating element to oscillate a certain distance in one direction and then to return. This continues as long as the heating element remains energized.

A rib 76 is provided on the rear upstanding portion 25b of the mounting piece 25 for retaining the removable cover 16 and the escutcheon casing 15.

It will thus be seen that the invention provides very simple, efficient and inexpensive oscillating mechanism. There are few parts and these are of a type having little wear or likelihood of getting out of order. Moreover, all parts are extremely light. The oscillations are produced by and in accordance with the heat given off by the heating element itself. This heat is taken off through a very small opening in the reflector and for only part of the time, which detracts but slightly from the total heat given off by the reflector and detracts even less from the appearance of the heater, the small opening being scarcely noticeable. The scheme of deriving oscillations from the energy of the heating element itself avoids the use of motors or other devices which use large amounts of current and which besides are expensive, heavy and bulky and subject to impairment because of being used in proximity to the high temperature heating element. In general, it appears that the device provided by the invention and the method of operation constitute a distinct advance in the art. It will be understood that when heat is referred to throughout the specification and claims that it includes as its equivalent, light, which may be admitted and cut off from an energizing unit by a shutter or in which the energizing unit may be moved into or out of the range of the source of heat, this including light, in timed relationship with and as a means of producing the oscillation.

While one embodiment of the invention has been particularly described, it is to be understood that the invention may be variously em-

bodied within the limits of the prior art and the scope of the subjoined claims.

We claim as our invention:

1. Oscillating mechanism for heat radiating devices, comprising in combination, a heat radiating element, an oscillating mounting for said element, means responsive to the heat of said heat radiating element for controlling the position of said oscillating mounting, and means controlling the passage of heat from said element to said means. 10

2. Oscillating mechanism for heat radiating devices, comprising in combination, a heat radiating element, an oscillating mounting for said element, means responsive to and deriving power from the heat of said heat radiating element for controlling the position of said oscillating mounting, and means controlling the passage of heat from said element to said means. 15

3. Oscillating mechanism for heat radiating devices, comprising in combination, a heat radiating element, an oscillating mounting for said element, a thermostat power device for operating said oscillating mounting, and means for controlling the passage of radiant heat from said element to said thermostat power device for energizing or de-energizing the latter from the former and thereby controlling the operation of said oscillating mounting. 20

4. Oscillating mechanism for heat radiating devices, comprising in combination, a heat radiating element, an oscillating mounting for said element, a thermostat power device for operating said oscillating mounting, means for controlling the passage of radiant heat from said element to said thermostat power device for energizing or de-energizing the latter from the former and thereby operating the oscillating mounting, and means also operated by said thermostat power device for controlling the action of said heat passage controlling means. 30

5. An oscillating radiant heater, comprising in combination, a base, a reflector oscillatably mounted on said base, a heating element mounted in front of said reflector, a thermostat power device adapted to be operated by heat radiated from said heating element, said power device being mounted behind said reflector within the range of heat from said heating element, a shutter in said reflector between said power device and said heating element, means for oscillating said reflector and heating element in response to the action of the power device produced by heat radiated to said power device from said heating element, and snap action means also operated in response to the action of said power device for operating said shutter. 45

6. An oscillating radiant heater, comprising in combination, a base, a pedestal, a fixed ring gear mounted on said pedestal, a mounting piece oscillatably mounted on said pedestal, an oscillating shaft mounted on said mounting piece, a gear segment mounted on said oscillating shaft and cooperating with said ring gear for oscillating the mounting piece, a front reflector wall, a heating element, a rear reflector wall mounted on said mounting piece, an escutcheon casing behind said rear reflector wall, a fluid filled thermostat container mounted in said escutcheon casing, said casing having cooling openings for said container, said reflector walls having slits for admitting heat from said heater element to said thermostat container, a shutter for alternately opening and closing said slits, a Sylphon bellows operated by fluid from 50 55 60 65 70 75

said thermostat container in one direction and operated in the other direction by resiliency and air pressure, means for oscillating said shaft from said Sylphon bellows, and escapement mechanism for operating said shutter from said shaft at each end of the reflector oscillation.

7. Apparatus as set forth in claim 6 in which said escapement mechanism comprises a spring arm and cam arm on said shaft, integral latch and shutter operating arms loosely mounted on said shaft, a spring between said spring arm

and latch arm for putting cumulative tension on the latch arm, when held, from said spring arm, a verge normally biased to hold said latch arm in extreme positions, and means cooperating between said cam arm and said verge for releasing said latch arm at each end of the spring arm stroke, said spring causing said latch and shutter operating arms to snap to opposite position.

LAURENCE S. HARRISON. 10
